(57) **CLAIM**

The ornamental design for a watch casing, as shown and described.

DESCRIPTION

FIG. 1 is a top plan view of a watch casing showing my new design;

FIG. 2 is a left side elevational view thereof;

FIG. 3 is a right side elevational view thereof;

FIG. 4 is a first end elevational view thereof;

FIG. 5 is a second end elevational view thereof;

FIG. 6 is a bottom plan view; and,

FIG. 7 is a top plan view showing the watch casing pivoted in an open position to reveal a second watch face.

The broken line showings are environmental only and form no part of the claimed design.
